VENDING APPARATUS

Eben M. Calder, Kansas City, and William H. Witte, Avondale, Mo., assignors to General Vender Manufacturing Company, a corporation of Missouri

Application May 11, 1939, Serial No. 273,006

6 Claims. (Cl. 312—36)

This invention relates to vending apparatuses, and more particularly to an apparatus for vending packaged goods, for example, soda waters in bottles.

The principal object of the present invention is to provide an apparatus for vending goods which may be controlled by a coin operated mechanism and wherein a single article may be dispensed from the apparatus upon a single actuation of the coin operated mechanism.

Further objects of the present invention are to provide a unit article supporting structure arranged to be mounted on a door for a cooler in such a manner that the unit carrying door may be interchangeably mounted on a plurality of coolers; to provide a rotatable bottle supporting unit formed of a non-corrosive, relatively light material such as aluminum; and to provide a combination lock and indicating member arranged to show the condition of the supported commodities and simultaneously prevent acceptance of coins when the commodities have been dissipated.

Other objects of the present invention are to provide a vending apparatus having a relatively large capacity for bottled goods; to movably mount the bottled goods in a tank adapted to contain a refrigerant; to maintain the bottled goods in upright condition; to provide an opening in the tank with which the bottles are aligned individually, whereby other bottles adjacent the opening may not be removed; to so arrange the opening that a plurality of groups of bottles may be respectively aligned therewith for extraction of the bottles individually from the cooler; to adjustably lock the bottle support in the cooler; to provide for successive rotation of the bottle support; and to provide improved parts and arrangements of parts in the construction of an easily operable, relatively economical and highly efficient vending apparatus of the character noted.

In accomplishing these and other objects of the present invention, we have provided improved details of structure, the preferred form of which is illustrated in the accompanying drawings, wherein:

Fig. 1 is a fragmentary perspective view of a vending apparatus embodying the features of the present invention and showing the coin actuated mechanism and the discharge or delivery opening from the tank.

Fig. 2 is a plan view of the vending apparatus, parts of the cover being broken away to illustrate the relation of the bottle support to the

storage compartment and the mechanism for rotating the support.

Fig. 3 is a vertical cross-sectional view through the vending apparatus particularly illustrating the mounting of the bottle support.

Fig. 4 is a detail bottom perspective view of the bottle support and mounting therefor.

Fig. 5 is a detail fragmentary side elevational view of a portion of the vending apparatus, the cooler and coin actuated mechanism housing being shown in vertical section to illustrate the relation thereto of the lock mechanism and mechanism for indicating the condition of bottles in the support.

Fig. 6 is a detail vertical cross-section through a portion of the bottle support illustrating the relation of a bottle to a bottle chamber in the support.

Referring more in detail to the drawings:

1 generally designates a vending apparatus embodying the features of the present invention which preferably includes a container or receptacle such as a tank or cooler 2 provided with conventional standards 3, Fig. 3, for supporting the same, the cooler being insulated as at 4 and being provided with an open upper end 5. A flange 6 preferably forming an overlapped edge of the outer cooler wall is arranged in the cooler adjacent the open upper end 5 thereof, which flange is preferably extended about the interior of the cooler, as shown in Fig. 3, for a purpose presently described.

A cover 7 is also provided of substantially the same size and shape as the open upper end of the cooler, which cover is preferably formed of a pair of sections 8 and 9 hinged together as at 10. The cover is of suitable construction and is preferably provided with insulation 11. As a matter of practice, the edges of the cover are preferably provided with an integral peripheral flange 12 adapted to seat on a gasket or the like 13 which may be suitably fixed to the upper edge of the cooler opening 5 or the lower face of the cover flange 12.

45 A suitable locking device 14 is provided on the cover in such a manner as to preferably connect the section 8 of the cover with the cooler to prevent unauthorized removal of the cover or contents of the cooler from the cooler.

50 Mounted on the bottom surface of the cover and preferably on the section 9 thereof is a casting or similar support 15 which comprises an arm 16 extending longitudinally relative to the cover and having an offset lug or the like 17 at its outer end engageable with the flange 6 on the

cooler to secure the cover in position. Oppositely disposed arms 18, Fig. 4, also form a part of the casting support 15, the arms 18 being disposed transversely of the cover 7 and preferably being provided with offset lugs 19 arranged for engagement with retaining devices similar to the flange 6 on the side walls of the cooler.

As particularly illustrated in Fig. 3, the casting 15 has a substantially centrally arranged hub 20 provided with an aperture for receiving the upper threaded end of a stud or the like 21, the stud being secured in position relative to the hub by a suitable retaining device 22. The lower end of the stud is also preferably threaded and provided with a retaining device 23 and preferably also provided with a washer or the like 24 for cooperating with the hub 20 of the casting 15 in rotatably supporting a bottle support or drum 25.

The drum 25 constitutes an important part of the present invention and preferably consists of an aluminum casting, the casting comprising a bottom bottle supporting plate 26 which is preferably perforate for reducing the material and weight of the casting. Vertically arranged partition members 27 are spaced about substantially the outer periphery of the bottom plate 26, the partition members being of substantially T-shape and having the webs 28 thereof directed inwardly, the webs terminating in reinforcing, enlarged portions 29. Brace members 30 which are preferably of substantially V-shape, with the strokes thereof directed outwardly, are preferably arranged vertically on the bottom plate 26 in inwardly spaced concentric relation to the partitions 27 and opposite alternate partitions. Spaced inwardly from the bracing members 30 are partitions 31 preferably similar in shape to, but smaller in size than, the partition members 27, the partition members 31 being arranged in concentric relation to the brace members 30 and partition members 27 respectively and being disposed between alternate brace members 30 and in alignment with alternate partition members 27.

Also as a matter of practice, the outer partition members 27 are provided with cutouts 32 to reduce the weight and cost of material of the casting.

In the construction of a casting of this character, it has been found that the ice water and sometimes brine, employed for cooling bottled goods supported by the casting, rapidly attacks plated steel for example, and not only discolors the water normally surrounding the bottled goods, thus making the commodities unattractive to purchasers, but also weakens the bottle supporting structures and tends toward their deterioration as well as interfering with proper actuation of the vending apparatus generally. By forming the casting of aluminum for example, or some similar non-corrosive, relatively light material, a material advantage is provided due to the strength which the casting provides over an assembled series of parts and due to overcoming the discoloration of cooling medium, as well as the prolongation of the effective life of the bottle support.

The bottom plate 26 of the casting is provided with a centrally apertured hub 33 for passing a portion of the stud 21, that portion of the bottom plate 26 opposite the hub 33 seating on the washer 24 and allowing the casting to rotate on the washer. The upper ends of the partitions and brace members 27, 31 and 30 are intercon-

nected by a top plate 34 which has a hub 35 similar to the hub 33 and arranged in oppositely disposed relation thereto for receiving the upper end of the stud 21 to center the casting on the stud, yet allow rotation of the casting on the stud.

The retaining devices 22 and 23 on the stud may be manipulated to draw the casting 25 substantially into engagement with an annular guide member 36 on the hub 20 of the casting 15 for the purpose of preventing wobbling of the casting, yet permitting rotation thereof in response to actuation of mechanism now to be described.

A top plate 34 is preferably provided for the casting 25 which, in the present instance, preferably comprises a Geneva gear wheel 37 on its outer periphery, the wheel 37 being provided with spaced slots 38 and adjacent concaved arcuately shaped indentations 39. The indentations 39 are each arranged between a pair of slots 38 and are each disposed in alignment with a chamber 40, 41 or 42, the chambers in turn being formed by and arranged between the concentric series of partitions 27, brace members 30 and partitions 31. It has been found preferable to provide ten chambers on the inner series, ten chambers on the intermediate series, and twenty chambers on the outer series of partitions and/or brace members to the end that forty chambers are preferably provided in all. Where forty chambers are provided, forty indentations are also provided for the Geneva gear wheel to the end that when the Geneva gear wheel is moved in increments or successively by means of engagement of the Geneva gear wheel with suitable actuating mechanism, the casting 25 is rotated a distance substantially equal to the space between the radial centers of the indentations.

The top plate 37 of the casting 25 is also perforated in a manner corresponding to the chambers 40, 41 and 42 in the interior of the casting, as shown at 43, the diameters of the perforations 43 being sufficient to pass the widest diameters of bottles 44 or the like containing goods to be vended so that the bottled or similarly packaged goods may be applied to and removed from the chambers in the casting.

As a matter of practice, one of the perforations 43 in the top plate 34 of the casting is plugged as at 45 and preferably marked as the starting point for setting the casting in such a manner that it may be subsequently continuously operated to dispense thirty nine bottled or otherwise packaged commodities without danger of losing the initial bottle or the like prior to actual purchase thereof by a coin.

In order to rotate the casting 25 in increments, corresponding to the size of a bottle or the like to be vended, a counterpart of the Geneva gear wheel 37 is provided which preferably constitutes a wheel 46 fixed to a vertically upwardly extending shaft 47 and fixed to the shaft by a fastening device 48. The wheel 46 is provided with an annular groove 49, the inner extremity of which is indented as at 50 to provide a series of preferably three recesses and an alternate series of the same number of convexly or arcuately shaped cam members 51 which recesses and cam members bound the inner periphery of the groove 49. Spaced pins 52 are also provided in the wheel 46 substantially midway between each of the cam members 51 and on a circumference approximately defined by a continuation of the circular plane of the cam members.

It is believed apparent that the vertically ex-

tending shaft 47 may be set in such a manner that the convexly curved cam members respectively engage a concavely curved indentation on the Geneva gear wheel 37 for locking the wheel and casting in desired position, and that when turned, the shaft 47 rotates the wheel 46 to effect engagement of one of the pins in an adjacent slot 38 for turning the wheel 37 until such time as the next succeeding cam member on the wheel 46 engages the next succeeding indentation on the wheel 37 to again lock the casting in position.

The shaft 47, as above indicated, extends upwardly and passes through the section 8 of the cooler cover member into a coin actuated mechanism housing 53 suitably secured to the upper surface of the cover member. The housing 53 contains substantially conventional mechanism which may be operated by insertion of a coin in the plunger device 54 for rotating the shaft 47 in increments upon application of a separate coin for each movement of the shaft.

In order to effect delivery of bottles or the like from the chambers in the casting individually and without exposing the other bottles to delivery upon payment of but a single coin, a delivery opening 55 is provided in the cooler cover which is elongated and preferably extends in a transverse direction relative to the cooler.

The delivery opening is bounded by a reinforced aperture 56 in one of the transverse arms 18, Fig. 4, of the casting 15 which secures the bottle supporting casting in position in the cooler, and is of a length substantially equal to a plurality of bottles contained in the cooler and, as in the present instance, the length of the opening is equal to the sum of the largest diameter of a total of three bottles.

The opening 55 is finished in construction by a plate 57 suitably secured to the cover and an auxiliary cover member 58 is preferably mounted on the plate 57 which is of a size adapting it for covering the delivery opening. The auxiliary cover is suitably pivotally mounted on the plate 56, and has a spring 59 normally holding the auxiliary cover 58 in closing relation to the delivery opening 55.

With the construction thus far described, it is apparent that the casting 25 being filled with bottles or the like to be dispensed and the casting being moved in increments by the cooperating Geneva gear wheels incidental to coin controlled actuation of the plunger device, the casting is rotated to individually present a single bottle below the delivery opening for dispensing one bottle upon application of a single coin to the plunger and coin controlled mechanism.

It is further desirable to indicate when the casting has been relieved of all the bottles holding commodities to be vended, and to this end, a boss 60, Fig. 5, is provided on the upper surface of the top plate 37 of the casting 25 at a point on the plate spaced from the starting point 45 a sufficient distance to prevent actuation of the vending apparatus when the last full bottle or the like of vendible commodity has been dispensed.

The boss 60 moves under a roller 61 mounted at one end of a lever 62 which is pivoted as at 63 on a supporting plate 64, the plate 64 interconnecting the arm 17 of the boss 15 with the shaft 47 to additionally support the shaft. The inner end of the lever 62 is pivotally connected to a control arm 65 which extends upwardly through the cooler cover under control of the slot and pin connection 66 with a supporting plate 67 mount-

ed in the housing 53. A spring 68 normally urges an ear 69 on the arm 65 into engagement with one end of a lever 70 which is pivoted to the plate 67, the other end of the lever 70 being engageable with an indicating device 71 which is hinged to the plate 67 as at 72, the indicating device underlying a window opening 73 when urged to such position by the lever 70.

The inner end 74 of the lever 70 is preferably weighted in such a manner as to move the indicating device 71 into the position illustrated in Fig. 5 when permitted to do so by lowering of the arm 65 upon raising the outer end of the lever 62 when the roller 61 rides over the boss 60 on the gear wheel 37 of the casting 25. As the inner end of the lever 70 is lowered under force of gravity aided by the spring 68, it is arranged to drop into the path of the inner end 75 of the plunger device 54, thus preventing actuation of the plunger device and avoiding acceptance of a coin when the casting has been relieved of commodities to be vended.

The operation of an apparatus constructed as described is as follows:

Assuming a cooler constructed substantially as shown in Fig. 3 to be provided with a cooling medium such as ice water, brine or the like, and assuming the section 8 of the cover 7 to be hinged outwardly relative to the casting 25, bottled or like goods 44 may be applied to the chambers between the concentric series of partitions and brace members. In the present instance, the casting accommodates thirty-nine bottles and has an empty chamber covered by the starting plug 45. The casting being rotatably mounted on the cover section 8, the cover may be moved bodily to any desired location and applied to the cooler 2 or any other similar cooler having an open upper end of approximately the size of 40 the cover member. The cover is applied to the cooler in such a manner that the lug 17 on the casting 15 engages below the inwardly extending end of the securing flange 6 on the cooler to secure the cover in position.

Where securing flanges are provided on the side walls of the cooler, the lugs 19 on the arms 18 also engage therewith to add rigidity of the mounting of the casting in the cooler. The cover section 8 of the cover may then be turned downwardly into engagement with the upper edge of the cooler and locked in position in the usual manner.

The casting having been initially set to place the starting plug 45 below the delivery opening 55, the vending apparatus is prepared to receive a coin which may be applied to the plunger device 54, which device, when actuated, turns the shaft 47 one increment to cause a pin 52 to engage in a slot 38 and move the gear wheel 37 a distance sufficient to align one chamber other than the starting chamber with the delivery opening 55. The auxiliary cover 58 may then be opened and a bottle, or otherwise packaged goods, may be extracted from the chamber underlying the opening. Because of the arrangement of the concentric series of chambers, it is apparent that only one bottle may be extracted at a time upon application of a single coin to the coin controlled mechanism and that a separate coin is required for each actuation of the vending apparatus and extraction of vendible goods therefrom.

When the casting 25 has been given a substantially complete rotation, all the vendible commodities will have been dispensed from the

apparatus and the boss 60 moves into engagement with the roller on the lever 62 to effect lowering of the arm 65. As the arm 65 is lowered, the weighted end 69 of the lever 70 drops and the other end of the lever 70 moves the indicating device 71 to a position below the window opening 73, thus indicating that the casting has been emptied of bottles or the like. At the same time, the weighted end of the lever 70 moves into the path of the plunger device 54 and prevents actuation of the plunger device to the end that coins will not be accepted when no commodities can be vended.

The cover, including the casting, may then be removed and a substitute refilled cover and casting supplied therefor, or the section 8 of the cover may merely be folded back and a fresh supply of bottled or like goods applied to the chambers of the casting so that the operation just described may be continued.

It is believed apparent, therefore, that a vending apparatus has been provided which is easily applied to or removed from a cooler; which accommodates a maximum of commodities; which efficiently dispenses such commodities; and which is strong, yet light, and not subject to rapid deterioration.

What we claim and desire to secure by Letters Patent is:

1. In an apparatus of the character described, a cover member having an opening, a casting rotatably mounted on the cover member for supporting bottled goods including a bottom plate member, an annular series of spaced partition members on said plate member, an annular series of brace members concentrically arranged relative to said partition members, and an annular series of partition members concentrically arranged relative to said brace members and first-named partition members, said partitions and brace members forming chambers therebetween respectively alignable with said opening for dispensing bottled goods from the chambers through the opening.

2. In an apparatus of the character described, a cover member having an opening, a casting rotatably mounted on the cover member for supporting bottled goods including top and bottom plate members, an annular series of partition members spaced between and connecting said plate members, an annular series of brace members concentrically arranged relative to said par-

tition members, and an annular series of partition members concentrically arranged relative to said brace members and first-named partition members, said partition and brace members forming chambers therebetween, said top plate member having perforations overlying said chambers, said chambers and perforations being respectively alignable with said opening for dispensing bottled goods from the chambers through the opening.

3. In an apparatus of the character described, a casing having a flange on the interior thereof, a cover removably mounted on the casing having an opening therein, a casting mounted on the bottom face of said cover having an arm provided with a flange engageable with said casting flange to secure the cover to the cooler, and a support rotatably mounted on said casting arranged to seat bottles.

4. In an apparatus of the character described, a casing having a flange on the interior thereof, a cover removably mounted on the casing having an opening therein, a casting mounted on the bottom face of said cover having an arm provided with a flange engageable with said casting flange to secure the cover to the casing, a bottle support rotatably mounted on said casting, and means on the cover engageable with the support for moving bottles supported thereby into individual alignment with the opening in the cover.

5. In an apparatus of the character described, a casing, a cover removably mounted on the casing having an opening therein, a support rotatably mounted on the cover having chambers for containing goods to be vended, means for moving said support to position a chamber below the opening in the cover, a boss on said support, a lever on said cover adapted to be actuated by said boss, and means controlled by said lever for locking said support moving means.

6. In an apparatus of the character described, a casing, a cover on the casing having an opening, a rust resisting casting rotatably mounted on said cover for supporting goods comprising a plate member, a series of spaced upright members arranged about said plate member and forming chambers therebetween, and means for rotating the casting in increments relative to said cover opening.

BEN M. CALDER,
WILLIAM H. WITTE.
